DESCRIPTION

U.S. PATENT DOCUMENTS

FIG. 1 is a perspective view of a golf ball retrieval device incorporating my new design;

2,609,198 9/1952 Armstrong .
2,962,321 11/1960 Fowler et al. .
3,149,872 9/1964 Ward .
3,922,027 11/1975 Nesselt .
3,982,781 9/1976 Tucker et al. .
4,045,068 8/1977 Nelson .
4,058,336 11/1977 Parkinson .
4,063,769 12/1977 Zimmer .
4,194,779 3/1980 Ouhashi .
4,253,668 3/1981 Ose .
4,522,438 6/1985 Logue .
4,974,894 12/1990 Dubow .
5,004,240 4/1991 Tsukamoto .
5,165,744 11/1992 Vogrin .
5,335,953 8/1994 Luther, Sr. .
5,395,146 3/1995 Liu et al. .
5,437,487 8/1995 Fulop .
5,460,366 10/1995 Pugh .

FIG. 2 is an enlarged front elevational view of a golf ball retrieval device, broken away for clarity of illustration;

FIG. 3 is a right side elevational view of the golf ball retrieval device of FIG. 2;

FIG. 4 is a rear elevational view of the golf ball retrieval device of FIG. 2;

FIG. 5 is a left side elevational view of the golf ball retrieval device of FIG. 2;

FIG. 6 is a top plan view of the golf ball retrieval device of FIG. 2;

FIG. 7 is a bottom plan view of the golf ball retrieval device of FIG. 2; and,

FIG. 8 is a fragmented enlarged bottom perspective view of a golf ball retrieval device.
